(57) **CLAIM**

The ornamental design for double fluted and twisted food container, as shown and described.

DESCRIPTION

FIG. 1 is a top isometric view of a double fluted and twisted container showing my design.

FIG. 2 is a left side elevation view thereof, the right side view, front view, and rear view being identical thereto.

FIG. 3 is a plan view thereof; and,
FIG. 4 is a bottom view thereof.
